(57) **CLAIM**

The ornamental design for an egg stack divider board, as shown and described.

DESCRIPTION

FIG. 1 is a perspective view of an egg stack divider board showing my new design;

FIG. 2 is a top plan view of the egg stack divider board;

FIG. 3 is a bottom plan view of the egg stack divider board;

FIG. 4 is a front side elevational view of the egg stack

divider board, the rear side view being identical thereto; and,

FIG. 5 is a right side elevational view of the egg stack

divider board, the left side view being identical thereto.
